Atty.

UNITED STATES PATENT OFFICE.

JULIUS J. WOLF, OF CINCINNATI, OHIO, ASSIGNOR OF ONE-HALF TO
PHILIPP GOLDSMITH, OF COVINGTON, KENTUCKY.

EXHIBITOR-FORM.

SPECIFICATION forming part of Letters Patent No. 434,102, dated August 12, 1890.

Application filed February 7, 1888. Serial No. 263,316. (No model.)

To all whom it may concern:

Be it known that I, JULIUS J. WOLF, a citizen of the United States, and a resident of the city of Cincinnati, in the county of Hamilton and State of Ohio, have invented certain new and useful Improvements in Exhibition-Forms, of which the following is a specification.

The several features of my invention and the advantages arising from their use, conjointly or otherwise, will be apparent from the following description:

In the accompanying drawings, forming part of this specification, Figure 1 is a side elevation of a form embodying my improvements. Fig. 2 is a vertical section of the same through the arm. Fig. 3 is a horizontal section through the shoulder-joint. Fig. 4 is an enlarged sectional view illustrating the preferred means of attaching the arm to the bust. Fig. 5 is a section through the lower end of the forearm; and Fig. 6 is a section through the end of the hand-piece, the two figures illustrating the means of attaching the hand to the forearm.

Heretofore the half-bust used in show-windows to exhibit made-up goods—such as coats, vests, cloaks, or other sleeved garments, and the like—have been constructed without an arm. The coat, dress, or other sleeved garment was adjusted over this half-bust, and the sleeve of the garment to be displayed was allowed to lie flat. Such a disposition of the sleeve detracted from the symmetry of the exhibit. To remedy such lack of symmetry, I have been accustomed to stuff cotton or paper into the sleeve to fill out the latter, and impart to it the appearance it would have when in actual use. This stuffing of the sleeve was a very slow and tedious operation, occupying from twenty to twenty-five minutes. To remedy this evil, I unite to this bust an artificial arm, quickly and easily detachable from the bust, and as readily again attached thereto. By means of this feature of my invention the arm can be immediately detached from the bust, slipped into the sleeve, the garment laid on the bust, and the operation is finished, and has not occupied over a part of one minute. When desired, by de-

taching the arm from the bust, the garment may be quickly taken from the bust without removing the latter from the show-window, and another garment adjusted thereto whose sleeve is filled by the artificial arm, which latter is reattached to the bust, which has in the meantime remained in its place in the show-window or on the show-counter.

Referring to the accompanying drawings, A indicates a half bust or body, preferably constructed in the shell or skeleton form. When it is desired, as is often the case, to hold the upper end of the bust more or less elevated above the ground or floor, it is convenient to employ one or more of the well-known props b, hinged to a cross-brace B. This half-bust is preferably made of some light substance, as papier-maché.

The preferred description of detachable connection between the shoulder-joint of the arm and the bust is as follows: The joint is provided with an extension or portion d³ of a cylindrical form, which latter is received in an opening in the cross-bar B. To give a better bearing to the plug d³, a cylinder b' is preferably set in the cross-brace B to receive the plug. The plug is held fast in the opening in the cross-bar or equivalent portion of the bust by the screw E, which screws into the plug and against the end of the cylinder or bearing. To better hold the screw E in the plug, the latter is preferably provided with a metallic or hard-rubber cylinder d⁴ internally screw-threaded, and the screw E engages this female thread in the plug or cylinder last mentioned. The description of shoulder-joint which I prefer to employ is a joint having a globular exterior. The bust is at the shoulder provided with a circular opening a. The edge of this opening a is preferably provided with a facing of leather or other suitable material a'. This facing strengthens the edge of the opening a, and also makes a suitable friction between this edge and the ball of the joint. When the screw E is tightened up, the ball D fits snugly into this circular opening a and forms therewith a ball-and-socket joint. The preferred mode of constructing this ball-and-socket joint is as follows: A central tongue d' and two side pieces d d are present. 100

These parts are preferably of wood or other strong material, while the curved sides d^2 , completing the ball, are made of a light substance, like papier-maché. The parts of the ball are hinged together by the screw C, passing through the center. The tongue d' terminates in the cylindrical plug or piece d^3 aforementioned, or in the piece whereby connection is made with the bust. The projecting side pieces d are rigidly attached to the arm F.

The preferred construction of the arm is as follows: The arm F is modeled of papier-maché, and, to afford the requisite stiffness and strength for the attachment of the ball D, is preferably provided with the wooden cross-piece or diaphragm f. The forearm H is attached to the arm F by a hinged ball G, preferably constructed in all respects similar to the hinged ball D, constituting one of the features of my invention. The forearm H is preferably modeled of papier-maché. It is provided at its lower end with a stiff diaphragm h, having the opening h'. The diaphragm h, or equivalent portion, which receives the extension from the hand, is, at its front, provided with the recesses h^2 and h^3 to accommodate the spring J. The recess h^2 is covered by the stiff plate h^4 . The hand I is provided with the projecting plug i. The spring J is a piece of wire set in the end of the plug i, and bent so as to form a shoulder j, whose tendency is to project upward; but it is limited in its upward movement by the loop i², which projects down through an opening i' in the plug i and passes around a pin i³. The spring J terminates in the thumb-piece j², by means of which it may be depressed. The stop i³ is set at a suitable distance in advance of the shoulder j. Other forms of spring-catches may be employed to hold the hand in position and still fall within the scope of my invention. To afford easy access to the thumb-piece j², the hand is preferably grooved out at i⁴. When the hand is put in position in the forearm, the plug i is pushed through the opening h' in diaphragm h until the shoulder j of the spring J has slipped under the plate h⁴ and rests in the recess h^3 . The plate h⁴ being now in position between the shoulder j and the stop i³ holds the hand firmly in position. Thus it is the work of only a few seconds to attach the hand to the forearm, or detach it therefrom.

Between the thumb and forefinger of the hand two springs K are set. These springs bearing against each other afford a means for holding a display-card between the thumb and forefinger.

While the various features of my invention are preferably employed together, one or more of them may be employed without the

remainder, and in so far as applicable may be employed with half-busts, busts, or figures other than the half-bust herein specifically described.

What I claim as new, and desire to secure by Letters Patent, is—

1. The combination of body A, having circular shoulder-opening a, cross-brace B, provided with cylinder b', hinged ball D, provided with tongues d d d' and clamp-screw C, and screw E, substantially as and for the purposes specified.

2. The combination of body A, having circular shoulder-opening a, cross-brace B, provided with cylinder b', hinged ball D, provided with tongues d d d' and clamp-screw C, and screw E, arm F, and forearm H, hinged to arm F, substantially as and for the purposes specified.

3. The combination of forearm H, having opening h' and recess h^2 h^3 , plate h^4 , hand I, provided with plug i, spring J, provided with shoulder j and thumb-piece j², substantially as and for the purposes specified.

4. The combination of forearm H, provided with diaphragm h, having opening h' and recess h^2 h^3 , plate h^4 , hand I, provided with plug i, spring J, provided with shoulder j and thumb-piece j², substantially as and for the purposes specified.

5. In a bust-figure, the hollow forearm having diaphragm h, provided with central opening h', one of whose edges is at one side beveled away, forming an inclined recess h^2 , the forward end of said recess being covered by the flat wall or plate h^4 , attached to the diaphragm near its outer edge and extending down over the end of the recess to the continued lines of passage-way h', the opposite side of the said edge of said passage-way being beveled away outwardly and downwardly, and the hand I, having the central tongued piece i, in which a coiled end for an elastic spring J, extending forward and bent downward and back in a loop i², and there provided with a flanged extension or lip J², is sunk, the loop i², playing in the opening i', and stop i³, fixed in the piece i in a plane which, when transverse to the length of the arm, passes between the shoulder j of the loop and the opposite side of said loop, the spring-piece J, inclining upward and forward from its point of attachment to piece i, and the plate h⁴, lying between the shoulder j and the stop i³ when the piece i of the hand is passed back through the passage h' of the diaphragm of the forearm, substantially as and for the purposes specified.

JULIUS J. WOLF.
